VESTEE ROBE

Jac Lewis, New York, N. Y., assignor to Royal Robes, Inc., New York, N. Y., a corporation of
New York

Application March 29, 1951, Serial No. 14,659

Term of patent 14 years

(Cl. D3—25)

To all whom it may concern:

Be it known that I, Jac Lewis, a citizen of the United States of America and a resident of New York, New York, has invented a new, original, and ornamental Design for a Vestee Robe, of which the following is a specification, reference being had to the accompanying drawing, forming a part hereof.

Figure 3 is a plan view of the body portion of the vestee robe in spreadout condition, the belt shown in Figures 1 and 2 being omitted.

I claim:

The ornamental design for a vestee robe, as shown and described.

JAC LEWIS.
